UNITED STATES PATENT OFFICE

2,402,697

HIGH-FREQUENCY VIBRATOR

Edwin E. Turner, Jr., West Roxbury, Mass., assignor to Submarine Signal Company, Boston, Mass., a corporation of Maine

Application May 18, 1938, Serial No. 208,568

8 Claims. (Cl. 177—386)

1

The present invention relates to a device for producing compressional waves and more particularly to such a device for producing supersonic frequencies in which a radiating element is so dimensioned with regard to the frequency to be produced that the compressional waves radiating form a beam.

The principles of the present invention may be applied both to compressional wave transmitters operated either electro-dynamically or by magnetostriction methods and the device may be applied both for sending a beam of compressional waves in air or in water but the invention principally applies to a water system in which the radiating element vibrates in the same phase throughout its entire surface.

In devices for producing high frequency compressional waves it has become common practice to drive the surface at a great many points in the same phase and this has been accomplished by the use of a plate in which are mounted a great number of magnetostrictive rods each of which is energized in the same manner by coils surrounding the rods. Another system which has been employed is to construct the vibrating system of a heavy plate at the back of which are projected concentric cylinders of conductive material.

In these systems as described in my prior patent application Serial No. 677,179, filed June 23, 1933, the plate and rods formed a vibrating unit of the equivalent of a half of a wave length in which the node was positioned in or near the plate but no particular attention was paid to the method of supporting the vibrating element in such a manner as to produce the greatest efficiency in the operation of the system.

In accordance with the present invention the system is so designed that the nodes in the system are situated in the rods or tubes and are all in substantially the same line so that the plate itself may be supported to allow the greatest freedom of motion of it as the radiating element.

The present invention will be more fully described in connection with the embodiments described in the specification below and shown in the accompanying drawings in which Fig. 1 shows a sectional elevation of the device in one form; Fig. 2 shows a partial similar sectional elevation as shown in Fig. 1 modified in detail, however, from this construction; Fig. 3 shows another modification of the device shown in Fig. 1; Fig. 4 shows a modification of the device shown in Fig. 3; and Fig. 5 illustrates a further detail of the modification shown in Fig. 1 with driving coils on both sides of the tube elements.

In Fig. 1, 1 indicates the radiating element with a flat surface on the outer side which is to be exposed to the propagating medium and with concentric tubes or rings 3, 4 and 5, respectively, on the inner side which are preferably formed as

2

an integral part of the radiating element. The plate 1 with the tubes 3, 4 and 5 is preferably a forging which is machined down to exact dimensions to make the tubes concentric with one another and spaced at an equal distance apart. These tubes are of such material and dimensions that together with the plate 1, which should be no greater in thickness than one-eighth of a wave length of the compressional wave to be propagated in the material itself, the system forms a one-half wave length vibrator for each and every tube in which the nodal lines of each tube lie in the same plane defined by the line C—C (or 6) as indicated in the figure. The plate 1, as indicated in Fig. 1, has an outwardly extending flange 7 which is extended backwards of the plate by means of the shoulder 8 so that the flange 7 likewise centers in the same plane as that indicated by the line C—C (or 6). The vibratory system is clamped by means of the flange between the outer plate 9 and the inner casing 10. The tubes 3, 4 and 5 are energized at their top portions which are situated in magnetic fields formed by outer and inner pole elements. The center tube 3 has direct current flux flowing across from the center pole piece 11 to the outer pole piece 12, the return path being through the cylinder 13 and the top plate 14. Similarly the end of the tube 4 rests in the magnetic field formed by the outer pole element 15 and the inner element 13' which is a part of the cylinder 13. The coil 16 produces the magnetizing flux across the end of the tube 3 while the coils 17 and 18 perform similar functions for the tubes 4 and 5. The alternating current for driving tubes is supplied by the coils 20, 21 and 22 which may be positioned on the inside of the pole faces, as indicated in Fig. 1, or on the outside of the pole faces, as indicated in Fig. 5, in which coils are on both the outside and the inside of the pole face elements.

In the system as shown in Fig. 1 the energizing coil is indicated as extending about one-third the distance from the end of the tube. As a matter of fact it is preferable to extend the application of the energizing force substantially further down the tube towards the nodal plane on the line C—C (or 6) and it should be noted in this connection that assuming the tube vibrates sinusoidally, which it may well do, the amplitude of motion one-half the distance from the end of the tube is still seven-tenths of the amplitude at the end of the tube and therefore substantially the same reactance will take place to the driving force and permit a greater and more efficient application of the driving force over the system.

With an arrangement such as shown in Fig. 1 the entire plate 1 moves with a uniform amplitude throughout the entire surface and this is substantially true not only of the front surface of the plate but also of the rear surface. In

other words, the entire plate moves as a uniform mass, the elastic force being exerted entirely between the line of node and the plate in the tube. In order to maintain this symmetry, therefore, it is necessary to position the supporting flange 7 in the rear of the plate in the same plane as the nodal plane and to allow the extension and compression of the supporting web to be confined entirely within the shoulder 8 and the flange 7 so that the plate may be freely supported.

A modification of this system is shown in Fig. 2. In this modification the plate 30 is provided with a flange 31 extending at right angles outward from the back of the plate. The plane of the nodes is positioned at the center of this flange, however, by undercutting the tubes as indicated at 32, 33 and 34. These tubes are cut sufficiently into the plate so that their nodal planes coincide with the plane of the flange 31.

In the modification shown in Figs. 3 and 4 the same principle as explained in connection with Figs. 1 and 2 is applied to a magnetostrictive driving system. In Fig. 3 the plate 40, which is the equivalent of 1 in Fig. 1, is provided with a great number of magnetostrictive small tubes or rods 41, 41, 41, etc., each surrounded by coils 42, 42 for energizing and driving the magnetostrictive tubes. The tubes 41 may be fixed in the plate 40 in any suitable way which in itself forms no part of the present invention. In this system as indicated, however, the tubes are so proportioned and adjusted that a vibrating system is formed in which the nodes of the tubes form a plane coinciding with the plane shown in the line A—A of Fig. 3. The flange 43 is extended backwards from the plate 40 and is situated in the same plane as that of the nodes as indicated by the line A—A.

In Fig. 4 the same driving means is shown as in Fig. 3 but here the plate 50 is undercut as indicated by 51, 51, 51, etc., to receive the small rods or tubes 52 which are of magnetostrictive material and driven by means of the coils 53. Line B—B indicates the plane of the nodes in this figure.

A modification of the arrangement of Fig. 1 is indicated in Fig. 5 in which both inner and outer coils 60 and 61 are provided for driving the tubes 3, 4 and 5. The alternating current flux due to these coils is induced in the end of the tube which is of conductive material as, for instance, some form of copper or copper alloy and is in effect an electrodynamically operated system in which the tubes are the current conductors in the moving magnetic field.

In the present invention the plate and the rods or tubes at the rear thereof form a vibratory system preferably of one-half wave length, the plate being of substantial thickness and uniform and the tubes likewise uniform so that the nodes of the system lie in the plane near the plate. For most efficient operation the plate should be of substantial thickness but not so thick that appreciable wave motion occurs in the material of the plate in a direction perpendicular to its surface. In other words, in the present system the front and rear of the plate move with substantially the same amplitude.

Having now described my invention, I claim:

1. Means for transmitting a beam of compressional waves comprising a plate and elements projecting from the back of the plate forming a vibratory system in which there is a node of vibration in said elements near said plate all lying in the same plane, means extending from the 75

rear portion of said plate into said nodal plane, said means providing a supporting flange lying in said nodal plane for supporting said plate.

2. Means for transmitting a beam of compressional waves comprising a plate, a plurality of concentric tubes formed as an integral part of said plate and projecting rearward therefrom normal to said plate, said tubes and plate forming a vibratory system having a nodal plane positioned in said tubes near said plate, means for supporting said plate at the edge thereof comprising a flange extending from the rear portion of said plate, said means having a supporting element lying in the plane of said nodes.

15 3. Means for transmitting a beam of compressional waves comprising a heavy plate having substantial thickness, a plurality of concentric tubes formed integrally with said plate but undercut in the plate whereby a vibratory system

20 is formed having a nodal plane coinciding approximately with the rear surface of said plate, a flange extending from the rear edge of said plate into said nodal plane having a supporting element coinciding with said nodal plane.

25 4. Means for transmitting a beam of compressional waves comprising a plate having a thin flange projecting from the rear of the plate and outward forming a supporting web for said plate, a plurality of magnetostrictive rods mounted on the rear of said plate and having a node near the plate line in a single plane, said plane coinciding with the plane of said supporting web.

30 5. Means for transmitting a beam of compressional waves comprising a plate having a thin flange projecting outward from the back surface of the plate forming substantially a continuous surface with the back surface of said plate, a plurality of magnetostrictive rods mounted in recesses cut in the rear of the plate, said rods having nodes lying substantially in a single plane and said recesses being cut so that the nodal plane coincides with the plane of said flange.

35 6. Means for transmitting a beam of compressional waves comprising a plate having a thin web extending outward from the rear edge of the plate and forming a supporting web for supporting the plate in vibration, a plurality of concentric tubes mounted on the rear of said plate and having nodes lying in a single plane coincident with said supporting web, said tubes being of conductive material and means immersing the free ends of said tubes in an alternating current magnetic field to substantially one half the distance to said nodes.

40 55 7. Means for transmitting a beam of compressional waves comprising a plate having a thin web extending outwardly from the edge of the plate for supporting the plate, a plurality of concentric tubes mounted on the rear of said plate, 60 means immersing the free ends of said tubes in an alternating current magnetic field comprising means forming a cylindrical direct current magnetic field across said tubes, and coils adapted to carry alternating current positioned on both sides of said tubes in said fields.

8. Means for transmitting a beam of compressional waves comprising a plate having a plurality of concentric tubes formed of a single piece of conductive metal integrally with said plate and so proportioned with respect to the frequency at which the system is to operate that the nodes are provided in the tubes near the plate in a single plane.
